ELECTRIC LAMP BASE

David Borowitz, Chicago, Ill., assignor to Bradley
Manufacturing Company, Chicago, Ill., a cor-
poration of Illinois

Application December 14, 1953, Serial No. 28,043

Term of patent 3½ years

(Cl. D48—20)

To all whom it may concern:

Be it known that I, David Borowitz, a citizen
of the United States, residing at Chicago, Illinois,
have invented a new, original and ornamental
Design for an Electric Lamp Base, of which the
following is a specification, reference being had
to the accompanying drawing forming a part
thereof.

In the drawing:

Fig. 1 is a front elevational view of an elec-
tric lamp base showing my new design;

Fig. 2 is a right hand side view thereof;

Fig. 3 is a rear view thereof; and

Fig. 4 is a top plan view thereof.

The left hand side view would be the same as
the right hand side view.

The broken lines indicating the lamp socket of
Figs. 1, 2 and 3 have been omitted from Fig. 4 for
convenience of illustration.

The dominant features of my new design lie
in the portions shown in full lines.

I claim:

The ornamental design for an electric lamp
base, substantially as shown and described.
